F. DUTCHER.
FIBER CASE RAILWAY TORPEDO.
APPLICATION FILED MAY 28, 1915.

1,211,114.

Patented Jan. 2, 1917.

UNITED STATES PATENT OFFICE.

FRANK DUTCHER, OF VERSAILLES, PENNSYLVANIA, ASSIGNOR TO CENTRAL RAILWAY SIGNAL COMPANY, OF PITTSBURGH, PENNSYLVANIA, A CORPORATION OF NEW JERSEY.

FIBER-CASE RAILWAY-TORPEDO.

1,211,114.

Specification of Letters Patent.

Patented Jan. 2, 1917.

Application filed May 28, 1915. Serial No. 31,033.

To all whom it may concern:

Be it known that I, FRANK DUTCHER, a citizen of the United States, residing at Versailles, in the county of Allegheny and State of Pennsylvania, have invented certain new and useful Improvements in Fiber-Case Railway-Torpedoes, of which the following is a specification, reference being had therein to the accompanying drawing.

5 My invention relates to improvements in fiber case railway torpedoes.

The object of my invention is to provide a torpedo of this character in which all metal for closing the case and holding the strap is dispensed with so that there are no metal parts to fly to injure by-standers, and having tapering ends so that the torpedo is less liable to be knocked off the track by the car wheels.

10 Another object of my invention is to provide a simple, cheap and effective torpedo having certain details of structure and combination of parts hereinafter more fully set forth.

15 In the accompanying drawings, Figure 1 is a perspective view of my improved torpedo. Fig. 2 is a bottom perspective view of Fig. 1. Fig. 3 is a longitudinal sectional view taken on the line 3—3 of Fig. 1. Fig. 20 4 is a bottom perspective view of a modified form of torpedo. Fig. 5 is a transverse sectional view of Fig. 3.

25 Referring now to the drawings, 1 represents the outer case of my improved torpedo and which is preferably made of a tube cut into the proper length and pressed down flat as shown in Figs. 1 and 2 of the drawings and having its ends formed with folds 2 also clearly shown in Figs. 1 and 2 of the drawings. The bottom 3 of the case is provided 30 adjacent its edges with the slits 4 and 5, and the portion 6 between the slits 4 and 5 is pressed downwardly and passing through said downwardly pressed portion of the bottom, and through the slits is the rail-attaching clip or strap 7, whereby the same is readily secured to the torpedo. The explosive compound 8 is preferably in tablet form and is surrounded by a wrapper 9 which has the 35 extended portions 10 extending within the folded ends of the case 1 and whereby there is a double covering for the explosive compound as fully shown in Fig. 3 of the drawings. It will be understood that the wrapper 50 40 45 50 55 9 has its ends open and when the ends of

the case 1 are folded, the wrapper necessarily is folded therewith and tightly closes the same.

Passing through the folded ends of the case 1 are two rows of stitching 11 and 12 which tightly closes the ends of the case. These two rows of stitching also pass through the extended ends 10 of the wrapper 9 and tightly seal the wrapper. The folded ends of the torpedo case 1 are dipped 65 into a waterproof composition 13 which tightly seals the ends of the case and also the folded ends 10 of the wrapper 9 and absolutely prevents any moisture entering either the folded ends of the wrapper or the 70 case. This waterproof composition also enters the openings formed by the two rows of stitching, and prevents any moisture entering the case 1 or the wrapper 9. By this construction and arrangement of parts it 75 will be seen that I have provided an absolutely water-tight case having a double thickness and in which both inner and outer casings are simultaneously closed by a single means such as the stitching. It might 80 be found necessary to dip the whole torpedo in a waterproof composition which would tightly seal the slits 4 and 5 in the lower face, and absolutely prevent any moisture entering the outer case around the wrapper. 85

90 In the modification shown in Fig. 4 of the drawing the case 1 is constructed in the same manner as that shown in Figs. 1, 2 and 3, but in order to prevent the slitting or piercing of the case 1, I have provided an additional tube 14 which is of a length approximately that of the explosive compound 8, and tightly fits around the outer case 1. This additional tube 14 is provided with slits 15 and 16 having the portion 17 bulged 95 downwardly and forming a space through which the rail-attaching clip 18 passes and whereby the rail-attaching strap or clip does not enter the outer case 1 of the torpedo and absolutely prevents any moisture entering the outer case on the outside of the wrapper 8. After the torpedo is constructed in the manner shown in Figs. 4 and 5 the whole torpedo is waterproofed with shellac or other waterproof composition which 100 firmly locks the tube 14 on the case 1 and at the same time additionally seals the outer folded ends of the case 1 to form a more water-tight case.

105 110 The object of forming tapered ends for

the wrapper and tube is to present a relatively thin edge for the wheel of the locomotive or car to run on thus avoiding a thick abrupt edge for the engagement of the car wheel which might force the torpedo off the track.

Having thus fully described my invention what I claim and desire to secure by Letters Patent is:

16. 1. A railway torpedo comprising an explosive tablet, a wrapper around the tablet in tubular form with open ends, an open ended tube surrounding the tubular wrapper and of substantially the same length, the wrapper and tube having their ends extending beyond the explosive and flattened, and a stitching extending through the ends of the wrapper and tube uniting them and closing the open ends of both the tubular wrapper and the tube.
15. 2. A fiber case railway torpedo comprising an explosive tablet, a wrapper therearound in tubular form with open ends, an open end tube inclosing the tubular wrapper, the ends of the wrapper and tube extending beyond the explosive substantially the same distance, and the edges of the tube and the wrapper folded inward to form extended tapered ends, and stitching passing through the ends of the tube and the tubular wrapper and closing their open ends.
20. 3. A fiber case railway torpedo, comprising a flattened tube, an explosive tablet

within the tube, means for closing the ends 35 of the tube, a second tube tightly fitting the first tube, and of a length less than that of the first tube, and a rail-attaching strap carried by said second tube.

4. A fiber case railway torpedo comprising 40 a flattened tube, an explosive tablet within the tube, means for closing the end of the tube beyond the explosive tablet, a tube tightly fitting the first-mentioned tube and of a length shorter than the same, a rail-attaching strap carried by the second tube, and means for holding the second tube on the first-mentioned tube, substantially as shown and described.

5. A fiber case railway torpedo comprising 45 a flattened tube, an explosive tablet within the tube, the ends of the tube beyond the end of the explosive tablet folded and flattened, a stitching passing through the flattened folded ends of the tube, a second tube 50 tightly fitting the first tube, and of a length less than the same, a rail-attaching strap carried by the second tube, and a waterproof composition covering the entire torpedo first 55 and securing the second tube to the first 60 tube, substantially as shown.

In testimony whereof I hereunto affix my signature in the presence of two witnesses.

FRANK DUTCHER.
